INVENTOR

BY *Victor J. Evans*

ATTORNEY

UNITED STATES PATENT OFFICE

JOSEPH D. HARDESTY, OF SEYMOUR, INDIANA

WRENCH

Application filed May 8, 1928. Serial No. 276,155.

My present invention has reference to improvements in wrenches and my primary object is the construction of a wrench that includes a stationary and a movable jaw 5 with screw means for adjusting the movable jaw with respect to the stationary jaw, together with means, associated with the shank of the stationary jaw designed to be gripped by the hand of the operator to cant the shank and to likewise impart a longitudinal movement of the movable jaw with respect to the stationary jaw, and whereby the gripping of the wrench will effect in producing a vise-like engagement between the jaws upon the object engaged therebetween, and likewise permit of the operator obtaining a fresh grip upon such object.

A further object is the provision of a wrench that comprises a stationary jaw having one of its inner edges formed with a sharpened tooth and integrally formed with an angularly arranged shank, a movable jaw arranged on the shank and having an actuating screw for adjusting the same toward or away from the fixed jaw, the movable jaw being also provided with a sharpened tooth to coengage with the first mentioned tooth and thereby produce a cutter for wire or the like, said shank being received in a hollow handle which is pivoted thereto and which has its outer end spring influenced. One end of the handle is in contact with the actuating screw, while the shank is provided with a web that passes through an opening in the hollow handle which web has its outer edge headed to provide a gripping element for the operator to permit of the shank being swung on its pivot or the handle being swung toward the shank to impart a longitudinal movement to the actuating screw and slide the movable jaw toward or away from the stationary jaw.

To the attainment of the foregoing and other objects which will present themselves as the nature of the invention is better understood, the invention further consists in certain other novel features of construction, combination and operative association of parts, one satisfactory embodiment of which

is disclosed by the accompanying drawings.

In the drawings:

Figure 1 is a side elevation of a wrench in accordance with this invention.

55

Figure 2 is a top plan view thereof.

Figure 3 is a bottom plan view thereof.

Figure 4 is an approximately longitudinal sectional view therethrough.

Figure 5 is a similar sectional view but showing the parts actuated to effect a vise-like gripping engagement of the jaws with an object therebetween.

Figure 6 is a transverse sectional view approximately on the line 6-6 of Figure 5.

Figure 7 is a plan view of the actuating screw.

Referring now to the drawings in detail, the numeral 1 designates the stationary jaw of my improvement. This jaw is formed on its inner face and what may be termed its top a central V-shaped extension 2 that affords a tooth. The shank 3 which is integrally formed with and, of course, arranged at right angles to the stationary jaw 1, has one of its edges, from its outer end, arranged at an angle and the said angle surface has a reduced portion to which is fixed one end of an angle or arched spring 4. The end of this spring is in contact with the inner and top wall of a hollow handle 5 in which the rear portion of the shank is received. A pivot 6 passes transversely through the inner end of the hollow handle 5 and through the shank 3.

Arranged for slidable movement on the shank 3, of course, outward of the handle 5, there is the movable jaw 7. This movable jaw is formed with a tooth 8 which is disposed opposite the tooth 2 of the stationary jaw. The movable jaw 7 has a threaded socket 9 arranged therein and in this socket there is screwed one end of the actuating screw 10 of the improvement. The screw 10 has an outer rounded operating head 11 which is knurled and the head has its outer face convexed, as at 11'. This convexed face is formed with a shank 12 whose outer end is enlarged and rounded to provide the same with a knob 13. The shank 12 is received in the restricted pas-

sage of a substantially T-shaped slot 14 in the inner end of the handle 5, the knob 13 being received in the widened passage of the said pocket. It is to be noted that the shank 12 and knob 13 are freely received in the T-shaped slot 14 and that the handle provided with the T-shaped slot is at all times in contacting engagement with the convex face 11' of the head. The handle 5, or what I will term the under face thereof is provided with an elongated opening 15 and through this opening there is freely passed a web 16 which is fixed to the shank 3. The web is in the nature of an elongated plate and the outer end thereof is integrally formed with a laterally extending portion which affords a head 17. The outer edge of the head is arched and the same is round in cross section.

Normally the parts of my improved wrench are arranged in the position best illustrated by Figures 1 and 4 of the drawings. The pocket 14 provides a loose connection between the handle 5 and one end 25 of the actuating screw 10. The shank 3 is notched in the usual manner to receive the rounded and knurled head of the actuating screw to permit of the free turning thereof to adjust the movable jaw 7 with respect to 30 the stationary jaw 1. When the device is adjusted to receive an element to be cut between the teeth 2 and 8 or to receive an object between the confronting and straight faces of the jaws 1 and 7, the operator 35 grasps the handle with the palm of his hand, and with his fingers engages the head 17, swinging the said head toward the handle and swinging the shank 3 on its pivot 6 against the tension of its spring 4, thus canting the jaw 1. This movement of 40 the handle will cause the inner wall provided by the widened passage of the pocket 14 to engage with the knob 13 of the actuating screw 10 and by virtue of such engagement to impart a longitudinal movement to the slidable jaw 7 with respect to the stationary jaw 1, thus automatically 45 effecting a vise-like engagement of the jaws with the article or obstacle therebetween. 50 While in the showing of the drawings I have illustrated the active faces of the jaws as straight, it is obvious that the said faces, not provided with the teeth 2 and 8, may be concaved and toothed.

While I have illustrated a satisfactory embodiment of my improved device, my features of invention are capable of extended application and I do not wish to be limited to the precise structure herein 55 shown and described.

Having described the invention, I claim:

A wrench comprising a jaw having a right angle shank extending therefrom, a jaw slidable on the shank having a 60 threaded socket entering from its rear face,

a screw threaded in the socket and having a knurled operating head whose outer face is convex and is provided with a reduced shank that terminates in a knob enlargement, a hollow handle in which the major portion of the shank is received and to which the shank, adjacent its point of entry in the handle is pivoted, said handle having a T-shaped slot in the inner end thereof to freely receive the shank and the knob of the screw therein, and said end of the handle having a direct bearing on the convex face of the operating head, and the bore of the handle being of a greater diameter than the thickness of the portion of the shank received in said handle, said handle having one of its faces provided with an opening, a web removably fixed on the shank and passing through the opening in the handle and said web having an outer laterally extending finger portion and a spring fixed on the shank exerting a pressure against one wall of the bore of the handle to normally force the finger portion through said opening.

In testimony whereof I affix my signature.

JOSEPH D. HARDESTY.
